UNITED STATES PATENT OFFICE

2,563,716

PORTABLE LUBRICANT PRESSURE PUMP

Marcel Garancher, Chicago, Ill., assignor to
Stewart-Warner Corporation, Chicago, Ill., a
corporation of Virginia

Application December 20, 1947, Serial No. 792,911

18 Claims. (Cl. 103—153)

1

The present invention relates to dispensing apparatus, and more particularly to a manually portable power operated pump for dispensing fluids such as lubricant.

A primary object of the present invention is the provision of a new and improved high pressure pump for dispensing fluids such as lubricants which is power operated and manually portable.

Another object of the invention is the provision of a new and improved motor operated fluid dispensing pump in which simplified means are provided for controlling discharge of fluid when the motor is operating.

A further object of the invention is the provision of a new and improved power operated lubricant pump in which discharge of lubricant from the pump is controlled by co-operating valve means including a single valve manually operable to open communication between the discharge side of the pump and the reservoir of the pump and thus discontinue discharge to the parts to be lubricated, or to close the communication thus established for effecting discharge from the pump.

A still further object of the invention is the provision of a new and improved power operated pump for dispensing fluids which has a reciprocating pumping means and an improved driving connection between the pump and the power means of exceedingly compact construction.

Another object of the invention is the provision of a new and improved pump for dispensing fluids such as lubricant which has rotary power means and a reciprocating pumping means coaxially arranged with each other and with a driving connection between the two for converting the rotary action of the power means to reciprocatory motion.

Yet another object of the invention is the provision of a manually portable pump for dispensing fluids such as lubricant, which is of compact and generally improved construction and is simple and inexpensive to manufacture and assemble, so that its cost is low, but which nevertheless is durable and functions in a very satisfactory manner.

These and other objects, advantages and capabilities of the invention will become apparent from the following description wherein reference is had to the accompanying drawings, in which:

Fig. 1 is an axial section through the pump with the power means shown in elevation and a portion of the carrying handle shown;

Fig. 2 is a sectional view taken on the line 2—2 of Fig. 1;

2

Fig. 3 is a developed view of the double helical cam slots or threads forming part of the driving connection between the power means and the pump plunger; and

Fig. 4 is a horizontal sectional view taken on the line 4—4 of Fig. 1, showing a planetary gearing forming part of the driving connection between the power means and the pump.

Referring to Fig. 1, it will be seen that the improved pump of the present invention has a body casting 10 which is adapted to be supported upon a lubricant reservoir 12 and which supports the other elements of the pump. The body casting has internal threads 14 corresponding to the external threads on the top of the lubricant reservoir 12 so that the pump may be readily engaged or disengaged from the reservoir. This reservoir may be specially constructed for the pump, or the body casting 10 may be so formed that it may be engaged upon conventional shipping containers for lubricant. The body casting 10 has a depending extension 16 of a length to terminate adjacent the bottom of the reservoir when the pump is in operative position, and it is provided with an axially extending opening of stepped diameter for housing the operating mechanism of the pump.

The power means for driving the pump comprises a small high speed electric motor 18 of, for example, $1/12$ horsepower, which has a base 20 that is engaged in an enlarged opening 22 in the top of the body casting. The base rests upon a ring gear 24 which is seated upon a shoulder 26 formed at the junction of opening 22 and a smaller opening 28 in the casting, and the base 20 is secured to the casting and the ring gear is locked against rotation by means of a series of bolts 30, shown in Figs. 1 and 4. These bolts extend through the shoulder 26 in casting 10, ring gear 24, and base 20 and have nuts 32 threaded on the outer ends thereof into firm abutting engagement with the top side of the base. Annular gaskets 34 are preferably interposed between the ring gear and shoulder and the ring gear and casting to form a lubricant-tight union between these parts.

The motor 18 drives a pump through epicyclic or planetary reduction gearing, best seen in Fig. 4, and it has a shaft 36 which projects axially into the opening 22 and which is provided with gear teeth 38, as indicated in Figs. 1 and 4, spaced from its lower end so that this portion of the shaft forms the sun gear of the planetary gearing. This gearing also includes three freely rotatable planet gears 40 meshing with the teeth on the motor shaft 36 and engaged with the previ-

ously mentioned stationary ring gear 24 so that these gears will be rotated in a counterclockwise direction, as seen in Fig. 4. They will also revolve around the axis of the shaft in a clockwise direction, thus rotating a driving member, indicated in its entirety in Fig. 1 by the number 42.

This driving member is disposed in an opening 44 in the depending extension 16 of the body casting in axial alignment with the motor shaft 36, and the planet gears rotate upon pins 46 fixed in a head 48 on the driving member. The upper ends of the pins are interconnected by a ring 50 which has apertures spaced to correspond with the spacing of the pins, and the pins extend through these apertures so that the ring is carried between the head of these pins and the upper end of the gears 40.

The driving member 42 has a depending sleeve-like extension consisting of a skirt 52 depending from the head of the driving member, an intermediate sleeve-like member 54 and a sleeve-like lower end member 56. The latter two members are secured to the skirt 52 on the head of the driving member by means of an external sleeve 58 having its opposite ends crimped over annular ribs on the lower end of the skirt 52 and the upper end of the lower end member 56, as indicated at 60 in Fig. 1. These members are additionally secured together by an axially extending crimp 62 in the periphery of the sleeve 58 engaged in aligned grooves in the skirt on the head of the driving member and the intermediate and lower sleeve-like members, as indicated in Fig. 2.

Driving member 42 is guided for rotation by cooperating means including an extension 64 on the motor shaft 36 below the gear teeth thereon which projects into an aperture 66 in the head 48 of the driving member and a counterbore 68 in the depending extension 16 of the body casting which receives the lower end of the lower sleeve member 56 for rotation therein. A simple thrust bearing is provided between the driving member and the end of the motor shaft consisting of a ball 70 inserted in the aperture 66 in the head of the driving member. It will be apparent that this connection between the head and shaft allows for rotation of the shaft and driving member at different speeds.

Rotary movement of the driving member 42 is converted to vertical reciprocating movement of an operating head assembly, indicated at 72 in Fig. 1, by cooperating cam follower means 74 carried in the operating head which engage in right and left-hand thread or cam slots 76 formed in the inner peripheral surface of the intermediate sleeve member 54 of the driving member. The operating head 72 is generally cylindrical and is adapted to be received in the opening defined within the driving member 42. A depending skirt 78 on the operating head slidably engages in a bore 80 in the depending extension 16 of the body casting and guides the vertical movement of this head. Rotation of the operating head is prevented by a plurality of splines in the wall of bore 80, one of which is shown at 82 in Fig. 1, cooperating with registering slots in the skirt of head 72.

At its upper end the operating head 72 has a diametrically extending cylindrical recess as indicated at 84 in Figs. 1 and 2 for receiving the two cam followers 74. These followers have a peripheral lip or tongue 86 that is adapted to be received in the opposite thread slots or grooves 76 in the intermediate sleeve 54 of the driving member. These projecting lips follow the slots 76

when the driving member is rotated and cause the operating head to be reciprocated vertically and thus to reciprocate a plunger 88 connected to the operating head in axial alignment with the motor shaft 36. As indicated in Figs. 1 and 2, the inwardly facing ends of the followers 74 are provided with flat bosses 90 which are in engagement with each other so that oscillation of the followers with respect to each other when the direction of movement of the operating head is reversed is not impeded and they will readily follow the thread slots.

The plunger 88 has a head 92 on its upper end which seats in a recess in the lower end of the operating head and is secured thereto by a pin 94 extending diametrically through the parts. The plunger extends through and is guided for vertical movement by means of a guide member 96 housed in an opening 98 in the lower end of the extension 16. Guide member 96 is held in position by a plug 100 threaded into a bore in the side wall of extension 16. This plug has a tip engaged in a slot in the side wall of the guide member 96.

Below the guide member the plunger 88 extends through a high pressure chamber 102 which is formed in part by a recess 104 in the lower end of guide member 96, and in part by a cavity 106 formed in an insert 108 threaded into the lower end of extension 16. A low pressure cylinder 110 is formed in this insert in communication with the high pressure chamber 102, and the plunger 88 has a piston 112 threaded on its lower end which is adapted to reciprocate in the cylinder 110. In Fig. 1 the plunger 88 and piston 112 are shown at the upper limit of their stroke. During the down or suction stroke the piston 112 is carried beyond the lower end of cylinder 110 so that lubricant will be fed to the cylinder from the reservoir through the lower end of the cylinder.

Communication between the high pressure chamber 102 and the pump cylinder 110 is controlled by a valve 114 surrounding the lower end of plunger 88 and urged by a spring 116 toward a seat formed on the upper end of the cylinder. As best seen in Fig. 1, this valve is in the form of a hollow cup 118 having an annular ridge on its lower side which engages upon a corresponding ridge formed on the upper end of the cylinder 110. A washer 120 forming a seat for the lower end of spring 116 is engaged upon an annular shoulder formed in the upper edge of the cuplike member 118, and sealing means 122 including a leather packing washer and a sealing ring of suitable material are disposed within the cuplike valve member to form a fluidtight seal between the plunger and valve.

An outlet port 124 for the high pressure chamber 102 is formed in the wall of guide member 96. This outlet port is closed by a ball check valve 126 urged to closed position by a spring 128 projecting from a recess in a plug 130 threaded into the outer end of a bore 132 formed in a lateral boss 134 on the extension 16. Through a drilled passage 136 the bore 132 is in communication with a discharge pipe or conduit 138 secured to the upper end of the body casting 10 by a suitable coupling sleeve 140. The outer end of this drilled passage 136 is closed by a plug 142 threaded therein. A coupler 144 of conventional construction for connecting the pump to a lubricant receiving fitting on a part to be lubricated is provided on the outer end of the discharge conduit 138.

Discharge of lubricant from the high pressure chamber 102 occurs during the down-stroke of

the plunger 88 due to the fact that the plunger has portions of different volumetric displacement. It will be noted in Fig. 1, where the plunger is shown at the top of its stroke, that the upper end of the plunger extending through the guide member 96 is approximately double the diameter of the lower end which extends through the high pressure chamber 102 and valve 114 into the pump cylinder 110. During the down stroke of the plunger its enlarged upper end will be projected into the high pressure chamber 102 and will displace a quantity of lubricant from this chamber through outlet port 124 equal to the amount by which the volumetric displacement of this projected part exceeds the volumetric displacement of the smaller lower end which has moved out of the high pressure chamber.

A bypass for returning to the reservoir lubricant pumped by the piston is formed by a radial port 146 intermediate the ends of the pump cylinder which communicates with an annular passage 148 formed in the insert 108. This latter passage is in communication with an inclined bore 150 in a lateral projection 152 on the lower end of extension 16 through an inclined passage 154. The need for accurate location of these passages is eliminated because the annular passage 148 will always establish communication between the radial port 146 and the inclined passage 154.

In accordance with one of the features of the present invention, control of flow of lubricant to the part to be lubricated is effected by controlling charging of the high pressure chamber 102 and this in turn is controlled by controlling flow through the bypass means. This control is effected through a manually operated plunger valve 156 engaged adjacent its lower end in the bore 150, and at its upper end in a bore extending through the top of the body casting 10. This plunger has a sleeve 158 disposed thereon above a pin 160 extending diametrically through the plunger. A spring 162 engaged at opposite ends upon the pin 160 and the top side of projection 152 urges the plunger upwardly until the upper end of sleeve 158 engages the underside of body casting 10, as shown in Fig. 1. At this position of the valve the bypass passage is open to the reservoir so that lubricant pumped by the piston will flow through the bypass back to the reservoir and hence insufficient pressure will be developed to open valve 114 leading to high pressure chamber 102. As a result the high pressure chamber will not be charged and, therefore, no lubricant will be discharged to the part to be lubricated even though the motor is operating. If desired, a sealing ring 153 may be secured in an annular groove in that portion of the periphery of the plunger valve which reciprocates in the bore 150.

For convenience in handling the pump, a handle 164, shown fragmentarily in Fig. 1, is threaded into a boss 166 projecting from the body casting 10. Preferably the plunger valve 156 projects through the body casting adjacent the boss 166 so that the plunger can be operated by the thumb or one finger of the hand which holds the pump. A bail 168 may also be provided on the reservoir 12 for carrying the pump from place to place.

Lubricant may be fed to the operating parts in the extension above the guide member 96 through an aperture in the motor base 20 which is closed by a screw plug 170. The gaskets 34

on each side of the ring gear 24 and a gasket 172 between a shoulder on the guide member 96 and a shoulder in the opening 80 in the extension 16 prevent escape of this lubricant. A sealing ring 174 of suitable material is also provided between the insert 108 and guide member 96 to prevent upward leakage of the lubricant being dispensed.

Lubricant in the extension flows to the interior of the driving member 42 through one or more ports 176 in the skirt 52 on the driving member, and the upper end of the operating head has a port 178 communicating with the space between the cams 74, while a second port 180 in the head feeds lubricant to the head of plunger 88. The skirt 78 on operating head 72 is also provided with one or more ports 182 suitably located adjacent its upper end to communicate with the interior of extension 16 and thus prevent hydraulic locking of this part.

In the operation of my improved pump, when the plunger valve 156 is at the position shown in Fig. 1, no lubricant will be discharged by the pump even though the motor 18 is operating because the lubricant fed to pump cylinder 110 is bypassed back to the reservoir 12 through radial port 146, annular passage 148, inclined passage 154, and bore 150. However, if the plunger 156 is depressed completely to close the end of inclined passage 154, the pump will deliver a maximum amount of lubricant because the lubricant drawn into the pump cylinder 110 on the suction stroke of the piston will be forced from the cylinder past valve 114 and into high pressure chamber 102 on the up stroke of the piston, thus charging this chamber. On the down stroke of the plunger 156 the larger upper end of this plunger will be projected downwardly into the high pressure chamber and its greater volumetric displacement, as compared with the smaller lower end of the plunger which moves out of the chamber, will force lubricant past check valve 126 into outlet passage 136 and thence through discharge pipe 138 to the coupler 144.

In order to eliminate the need for accurately relating the volume of lubricant pumped by the piston 112 on its up stroke to the volume discharged by plunger 88 on its down stroke, the piston is made of such diameter that a slight clearance will exist between the piston and the walls of cylinder 110. Thus, if the volume displaced by plunger 88 is less than the capacity of piston 112, the excess will escape around the piston back to the reservoir. It is also to be noted that a suction is produced in the high pressure chamber 102 by upward movement of the larger end of the plunger. This assists in creating a flow of lubricant to this chamber when the plunger valve 156 is closed.

From the above description of a preferred embodiment of the invention it will be seen that the objects of the invention are attained. It will also be apparent that numerous variations and modifications thereof may be made without departing from the underlying principles of the invention. I, therefore, desire by the following claims to include within the scope of the invention all such variations and modifications by which substantially the results of my invention may be obtained through the use of substantially the same or equivalent means.

I claim:

1. In a lubricant pumping apparatus having a lubricant reservoir and power means for operating the apparatus, the combination com-

prising a lubricant discharging pump including a piston and plunger assembly reciprocable in one direction by said power means for charging said pump and in the opposite direction for discharging lubricant to the part to be lubricated, means forming a bypass for lubricant between said pump and reservoir, and means for controlling charging of the pump including a manually operated valve controlling flow of lubricant through said bypass, and a valve automatically operated to admit a charge of lubricant to said pump during movement of the piston and plunger assembly in the one said direction when said manually operated valve is operated to close said bypass.

2. A lubricant pumping apparatus as set forth in claim 1, wherein the automatically operating valve is preloaded automatically to prevent charging of said pump when said manually operated valve is operated to open said bypass.

3. In a lubricant pumping apparatus having a lubricant reservoir, the combination comprising a pump cylinder having an inlet communicating with said reservoir, a power operated piston for discharging lubricant from said cylinder, means forming a bypass establishing communication between said cylinder and reservoir, a chamber for receiving lubricant discharged by said piston to charge said chamber, differential means operating with said piston to force lubricant from said charged chamber to the part to be lubricated, valve means between said cylinder and said chamber controlling charging of the latter, said valve means being preloaded to prevent flow of lubricant to said chamber when said bypass is open, and a manually operated valve for controlling flow of lubricant through said bypass and thereby controlling charging of said chamber.

4. In a lubricant pumping apparatus having a lubricant reservoir and power means for operating the apparatus, the combination comprising a lubricant discharging pump including a differential plunger operated by said power means, means forming a bypass between said pump and reservoir, means for connecting said pump to a part to be lubricated including a chamber, said plunger extending through said chamber and having a part of increased volumetric displacement adapted to be projected therein upon movement of the plunger in one direction for forcing lubricant to the part to be lubricated, and cooperating means including a manually operated valve controlling said bypass and a valve automatically operated to admit lubricant to said chamber upon movement of the plunger in the opposite direction when said manually operated valve is in a position closing said bypass.

5. In a lubricant pumping apparatus having a lubricant reservoir and power means for operating the apparatus, the combination comprising a pump cylinder having an inlet communicating with said reservoir, means forming a bypass establishing communication between said cylinder and reservoir, a chamber communicating with said cylinder for receiving lubricant discharged therefrom to charge the chamber, a piston in said cylinder for discharging lubricant therefrom, a differential plunger operated by said power means for operating said piston, said plunger having a portion of increased volumetric displacement projected into said chamber upon movement of said plunger carrying said piston through its suction stroke, said portion being withdrawn from said chamber to permit charging thereof upon movement of said plunger ac-

tuating said piston in a discharging direction, cooperating means controlling charging of said chamber including a manually operated valve controlling flow of lubricant through said bypass, and a valve automatically operated to admit a charge of lubricant to said chamber when said manually operated valve is operated to close said bypass.

6. A lubricant pumping apparatus as set forth in claim 5, wherein the automatically operated valve is preloaded automatically to prevent charging of said chamber when said manually operated valve is operated to open said bypass, said latter valve being biased to open position.

7. In a manually portable lubricant pumping apparatus having a lubricant reservoir, the combination comprising a body casting for supporting the operating parts of said apparatus including a portion adapted to be removably engaged upon said reservoir, a handle on said body casting for manipulating said compressor apparatus, a power operated lubricant discharging pump supported by said body casting means forming a bypass between said pump and reservoir, means for connecting said pump to the part to be lubricated, and cooperating valve means for controlling the flow of lubricant to the part to be lubricated including a manually operated valve for controlling the flow of lubricant through said bypass means and an automatically operating valve preloaded to prevent flow of lubricant to the part to be lubricated when said bypass means is open, said manually operated valve having a plunger supported in said body casting including a manipulatable part positioned to permit operation thereof by a finger of the hand holding said apparatus.

8. In a lubricant pumping apparatus having a lubricant reservoir, the combination comprising a lubricant discharging pump having a reciprocable piston and plunger assembly, rotary power means, a hollow generally cylindrical driving member rotated by said power means, an operating head connected to said plunger assembly and constrained for reciprocatory movement, said head having a diametrically extending cylindrical opening, cooperating means for reciprocating said operating head and plunger assembly when said driving member is rotated including right and left-hand thread slots in the inner periphery of said hollow driving member and duplicate followers conformed to be loosely received in the diametrically extending opening in said operating head and having projecting lips to engage in said thread slots at diametrically opposite points, the confronting ends of said followers having correspondingly located projecting abutments to provide bearing surfaces between said followers for facilitating relative axial oscillation of said followers while following said thread slots, means for connecting said pump to a part to be lubricated, and manually operated control means for controlling flow of lubricant from said pump to a part to be lubricated.

9. A lubricant pumping apparatus as set forth in claim 8, wherein the rotary motor, driving member, operating head, and reciprocable plunger are axially aligned.

10. In a lubricant pumping apparatus having a lubricant reservoir, the combination comprising a body casting having a portion adapted to be removably engaged with said reservoir and a hollow extension terminating adjacent the bottom of said reservoir, a pump cylinder in said extension adjacent the lower end thereof, a pis-

ton in said cylinder, a plunger for reciprocating said piston projecting longitudinally of said extension, rotary power means on the opposite end of said body casting from said cylinder having a shaft projecting into said extension, a driving member in said extension, means operatively connecting said power means and driving member, an operating head in said extension operatively connected to said plunger, means for effecting reciprocatory movement of said head and plunger upon rotation of said driving member including right and left-hand thread slots in said driving member and cam follower means carried by said operating head for engaging in said slots, means secured to said casting for connecting said apparatus to a part to be lubricated, and manually operated control means supported on said casting for initiating or discontinuing flow of lubricant to said part.

11. In a lubricant pumping apparatus having a lubricant reservoir, the combination comprising a lubricant discharging pump including a plunger and piston reciprocated thereby for charging said pump upon movement of the same in one direction and for discharging lubricant to the part to be lubricated upon movement in the opposite direction, rotary power means, means for reciprocating said plunger including a driving member rotated by said power means and a reciprocal operating head connected to said plunger, said driving member and head having interengaging right and left-hand thread slots and cam follower means cooperating to reciprocate said head and plunger when said driving member is rotated, means forming a bypass between said pump and reservoir, means for connecting said apparatus to a part to be lubricated, and means for controlling charging of the pump including a manually operated valve controlling flow of lubricant through said bypass and a valve automatically operated to admit a charge of lubricant to said pump during movement of the piston and plunger assembly in the said one direction when said manually operated valve is operated to close said bypass.

12. In a lubricant pumping apparatus having a lubricant reservoir and power means for operating the apparatus, the combination comprising a lubricant pump including a plunger operated by said power means having portions of different volumetric displacement, means for reciprocating said plunger, including a driving member rotated by said power means and a reciprocal operating head connected for reciprocating said plunger, said driving member and head having interengaging right and left-hand thread slots and cam follower means cooperating to reciprocate said head and plunger when said driving member is rotated, means forming a bypass between said pump and reservoir, means for connecting said pump to a part to be lubricated including a chamber, said plunger extending through said chamber and having a part of increased volumetric displacement adapted to be projected therein upon movement of the plunger in one direction for forcing lubricant to the part to be lubricated, cooperating means controlling the flow of lubricant to said chamber including a manually operated valve controlling said bypass, and a valve automatically operated to admit lubricant to said chamber upon movement of the plunger in the opposite direction when said manually operated valve is operated to a position closing said bypass.

13. In a lubricant pumping apparatus having

a lubricant reservoir and power means for operating the apparatus, the combination comprising a pump cylinder having an inlet communicating with said reservoir, a piston in said cylinder, a differential plunger for reciprocating said piston, means for reciprocating said plunger including a driving member rotated by said power means and a reciprocable operating head connected to said plunger, said driving member and head having interengaging right and left-hand thread slots and cam follower means cooperating to reciprocate said head and plunger when said driving member is rotated, means forming a bypass establishing communication between said pump cylinder and reservoir, a chamber communicating with said cylinder and receiving lubricant discharged by said pump for charging the chamber, said plunger having a portion of increased volumetric displacement adapted to be projected into said chamber for forcing lubricant therein to the part to be lubricated when said chamber is charged, and means for controlling charging of said chamber including a manually operated valve controlling flow of lubricant through said bypass, and a valve automatically operated to admit a charge of lubricant to said chamber during the discharge stroke of said piston when said manually operated valve is operated to a position closing said bypass.

14. In a lubricant pumping apparatus continuously operable power means, lubricant pumping means including high and low pressure chambers, a piston in said low pressure chamber for pumping lubricant to charge said high pressure chamber, a differential plunger operated by said power means for operating said piston, said plunger having areas of different volumetric displacement extending through said high pressure chamber for effecting discharge of lubricant from the apparatus when the plunger is moved in a direction to carry said piston through its suction stroke, means forming a passageway for bypassing lubricant from said low pressure chamber to said reservoir, a manually controlled valve to control communication through said bypass passageway, means forming a passageway to establish communication between said chambers, a check valve controlling communication between said two chambers, and a spring to bias said valve to closed position, said spring exerting sufficient force to resist opening of said check valve when said bypass passageway is open but being yieldable to the pressure generated in said low pressure chamber when said bypass passageway is closed during the discharge stroke of the piston.

15. In a lubricant pumping apparatus the combination comprising a body member including a generally tubular extension, means in said extension forming a first and second pumping chamber and a passageway interconnecting said pumping chambers, a piston in said first chamber for pumping lubricant under relatively low pressure to said second chamber to charge the same, a reciprocatory plunger for operating said piston having areas of different volumetric displacement extending through said second chamber for effecting discharge of lubricant therefrom under high pressure while said piston is being retracted by said plunger, rotary power means, a driving member in said extension rotated by said power means, means in said extension to establish a driving connection between said driving member and a plunger including means for reciprocating said plunger in response to rotary movement of the driving member, means forming a by-pass

11

passageway between the outlet end of said first chamber and said reservoir, means for establishing a connection between the second chamber and a part to be lubricated, a manually controlled valve for controlling flow of lubricant through said by-pass, a check valve controlling communication between said two chambers, and means to bias said check valve to closed position with a force sufficient to resist opening of said valve during the discharge stroke of said piston when said by-pass passageway is open, said means yielding to the pressure generated by said piston when said by-pass passageway is closed during the discharge stroke of the piston to admit a charge of lubricant to said second chamber.

16. In a lubricant pumping apparatus having a lubricant reservoir, the combination comprising a lubricant discharging pump having a reciprocable piston and plunger assembly, rotary power means, a hollow generally cylindrical driving member, epicyclic reduction gearing driven by said rotary power means and connected to said driving member for driving the latter, an operating head connected to said plunger assembly and restrained for reciprocatory movement, said head having a diametrically extending cylindrical opening, cooperating means for reciprocating said operating head and plunger assembly when said driving member is rotated including right and left hand thread slots in the inner periphery of said hollow driving member and duplicate followers conformed to be loosely received in the diametrically extending opening in said operating head and having projecting lips to engage in said thread slots at diametrically opposite points, the confronting ends of said followers each having correspondingly located projecting abutments to provide bearing surfaces between said followers for facilitating relative axial oscillation thereof in following said thread slots, means for connecting said apparatus to a part to be lubricated, and

12

manually operated control means for controlling flow of lubricant from said apparatus to a part to be lubricated.

17. In a lubricant pumping apparatus, the combination comprising a reservoir, a body member secured to one end of said reservoir and having a tubular extension depending therein, lubricant pumping means in the lower end of said extension including a reciprocable piston and plunger assembly, rotary power means on said body member having a rotatable shaft projecting into said extension, reduction gearing in said extension driven from said shaft, a generally cylindrical shaped driving member closed at one end and rotatably journaled at its other end in said extension, said driving member having an axial socket in its closed end and said shaft projecting into said socket to form a pivot axis for the said end of the driving member, cooperating means on said driving member and plunger for reciprocating the latter in response to rotary movement of the driving member, means for connecting said pumping means to a part to be lubricated, and manually controlled means to control flow of lubricant from said apparatus to the part to be lubricated.

18. A lubricant pumping apparatus as defined in claim 17 wherein the cooperating means on said driving member and plunger for reciprocating the latter in response to rotary movement of the driving member includes right and left hand thread slots on one of said parts and diametrically oppositely disposed thread slot followers fixed to the other part.
